UNITED STATES PATENT OFFICE.

P. W. GATES, D. R. FRASER, AND THOS. CHALMERS, OF CHICAGO, ILLINOIS.

CUT-OFF GEAR FOR STEAM-ENGINES.

Specification of Letters Patent No. 22,361, dated December 21, 1858.

To all whom it may concern:

Be it known that we, P. W. GATES, D. R. FRASER, and THOMAS CHALMERS, of Chicago, in the county of Cook and State of Illinois, 5 have invented a new and Improved Variable Cut-Off Gear for Steam-Engines; and we do hereby declare that the following is a full, clear, and exact description of the same, reference being had to the accompanying 10 drawings, making part of this specification, in which—

Figure 1 is a front elevation. Fig. 2 is a vertical section in a plane at right angles to Fig. 1. Fig. 3 is a horizontal section in the 15 plane indicated by the line α , α , in Fig. 1. Fig. 4 is a back view of the rocking frame and its appendages by which the cut-off valve is lifted.

Similar letters of reference indicate corresponding parts in the several figures.

This invention consists in a novel construction of two sliding toe-pieces and a mode of applying the same to a rocking frame operated by the steam-engine, in combination with a double lifter attached to the stem of the cut-off valve and with a governor or other regulating apparatus to produce and vary the action of the cut-off for the purpose of controlling the speed of 30 an engine.

To enable others skilled in the art to apply our invention to use, we will proceed to describe its construction and operation.

A, is a valve box containing the cut-off 35 valve which may be of the balanced puppet or any other known kind, and therefore does not need to be shown. This valve box is intended to be placed on the valve chest of a steam engine or otherwise applied so that 40 all the steam supplied to the engine must pass through its valve.

B is the valve stem working vertically through the top of the box A, and entering a box C, which is attached to the valve-box 45 by standards F, F, and within which the stem has attached to its upper end a cross-head D, to the ends of which are attached two guide rods E, E, which are parallel with the valve stem and which pass through guide 50 holes in the bottom of the said box C. The lower parts of these rods E, E, have screw threads cut upon them and are fitted with nuts b, b, between which and the bottom of the box C, there are spiral springs a, a, coiled 55 upon said rods for the purpose of exerting a downward pressure upon the valve stem to

close the valve. The box C is merely to inclose the crosshead and the upper ends of the valve stem and guide rods, and its bottom contains the guides for said stem and 60 rods to prevent the stem turning.

G, is a crosshead secured to the valve stem and having its ends bent laterally at right angles as shown at e, e', in Fig. 3, to make it constitute a double lifter.

H, is a rock shaft arranged horizontally with its axis in the same plane as the axis of the valve stem, and I is a bearing which supports the said rock shaft. This rock shaft carries the rocking frame J, to which 70 are fitted the two sliding toe-pieces L, L', which by the rocking motion of the frame J, are made to act alternately upon the projections e, e', of the lifter; L, upon e, and L' upon e', and thus lift the valve open. These 75 toe-pieces are fitted to slide past each other in a longitudinal recess formed in the back of the rocking frame and are furnished with tail-like pieces h, h', which project downward through an opening in the bottom of 80 the recess in the frame in such a manner that they stand on opposite sides of a roller i, fitted to a stud j, which is attached to a slide, M, that is fitted to slide up and down on the valve stem. The faces of the said tail-like 85 pieces which are next to the roller are inclined so as to approach each other toward their lower extremities, as shown in Figs. 1 and 4. The toes k, k', on the toe-pieces have angular extremities which are arranged 90 to act upon the bent extremities e, e', of the lifter.

The toe-pieces are secured in the frame G, by screws f, f', which pass through slots g, g', in the said frame and screw into the 95 said pieces; and the screws f, f', serve to attach to the toe pieces a spring N, which exerts a tendency to force them toward the ends of the frame as far as permitted by their tails h, h', which come in contact with 100 the roller i, on the opposite side to their respective toes k, k'.

The rockshaft H is furnished with an arm P, which is intended to be connected with an eccentric on the crankshaft of the engine or to have some connection with the engine which will cause it to oscillate once back and forth during every revolution thereof so that the toes acting upon the lifters will lift the cut-off valve to admit steam to the cylinder for every stroke of the piston.

The slide M, is connected with a rod l,

which may be supposed to be connected with a governor or provided with a screw adjustment to raise or lower said slide and its stud *j*, and roller *i*. There is a stationary slotted 5 guide *R*, attached to the top of the valve box *A*, for the roller *i*, to work in, to keep the slide *M*, from turning on the valve stem.

The operation is as follows: As the toe pieces *L*, *L'*, are caused to lift the valve by 10 their action below the laterally projecting ends *e*, *e'*, of the lifters, produced by the rocking movement of the frame *J*, their toes *k*, *k'*, are caused, both by the arc-formed movement of the rocking frame and by reason 15 of the toe-pieces being drawn into the frame by the action of their respective tail-like pieces *h*, *h'*, against the roller *i*, as the toes are raised, to slide under the ends *e*, *e'*, until the toes, if the roller *i*, is not too high 20 up, slip from under the laterally projecting ends *e*, *e'*, and let the valve drop suddenly and close. Fig. 1 shows the toe *k*, as just about to escape from the end *e*, and let the valve drop. As the toes descend with the 25 rocking movement of the frame *J*, they work down the inner faces of the projection *e*, and are thereby forced into the frame *J*, until, after working clear of the said faces, the spring *N*, forces them out again to positions 30 to act under the said projections *e*, *e'*, as they rise again. The time of the escape of the toes to let the valve drop depends upon the position of the stud *j*, and roller *i*; the lowering of the said stud and

roller between the inclined surfaces of the 35 tail pieces *h*, *h'*, forcing them farther apart, and thereby drawing in the toe-pieces so that they will escape earlier in the stroke of the piston, and the raising of said stud and roller producing an opposite effect. The 40 stud and roller may be raised so high as to permit the spring *N*, to keep the toe-pieces always so far out as to prevent the escape of the toes and compel the valve to be lowered gradually, as well as raised, by the toes, 45 and thus permit the piston to work under a full head of steam throughout the whole stroke. In applying a governor, the rod is so connected with it as to lower the slide *M*, and the attached stud *j*, and roller *i*, as any 50 tendency to increased speed of the engine is developed, and vice versa.

What we claim as our invention, and desire to secure by Letters-Patent, is:—

The two sliding toe pieces *L*, *L'*, constructed as described and applied within the rocking frame *G*, to operate substantially as herein described, in combination with the double lifters *G*, *e*, *e'*, attached to the valve stem with a stud and roller *j*, *i*, or their 55 equivalent connected with a governor or otherwise made movable.

P. W. GATES.

D. R. FRASER.

THOMAS CHALMERS.
